UNITED STATES PATENT OFFICE

ALWIN L. TOEWS, OF ORANGE COVE, CALIFORNIA

DESIGN FOR A PEDESTAL LAMP OR SIMILAR ARTICLE

Application filed January 9, 1933. Serial No. 46,762. Term of patent 7 years.

To all whom it may concern:

Be it known that I, ALWIN L. TOEWS, a citizen of the United States, and a resident of Orange Cove, county of Fresno, State of California, have invented a new, original, and ornamental Design for a Pedestal Lamp or Similar Article, of which the following is a specification, reference being had to the accompanying drawing, forming part thereof.

The figure is a perspective view of a pedestal lamp showing my new design.

Referring to the drawing in detail my invention comprises a pedestal lamp having the appearance of natural growth and presenting a cellular structure characterized by large and small veins and large and small perforations disposed promiscuously over the entire surface thereof.

I claim:

The ornamental design for a pedestal lamp, or similar article, substantially as shown and described.

ALWIN L. TOEWS.
